UNITED STATES PATENT OFFICE.

JOHN R. CLARK, OF EARLE, ARKANSAS.

BILLIARD-CUE TIP.

1,164,781.

Specification of Letters Patent. Patented Dec. 21, 1915.

Application filed April 24, 1915. Serial No. 23,683.

To all whom it may concern:

Be it known that I, JOHN R. CLARK, a citizen of the United States, residing at Earle, in the county of Crittenden and State of Arkansas, have invented certain new and useful Improvements in Billiard-Cue Tips, of which the following is a specification, reference being had to the accompanying drawings:

10 This invention relates to an improved billiard cue tip, and has for its primary object to provide very simple and inexpensive means for repairing or re-tipping billiard cues.

15 The invention has for a further detail object to provide an improved construction of the tip receiving ferrule which is formed on one end with a seat for a leather tip, and is provided with means for permitting of 20 the secure fastening of the leather tip to the end of the cue by liquid cement or other suitable adhesive.

25 The invention has for a further general object to improve and simplify the construction of devices of the above character, whereby the repairing of billiard cues may be greatly expedited and the tip easily and securely applied to the end of the cue without necessitating the use of screws, pins or 30 analogous fastening elements.

With the above and other objects in view, my invention consists in the novel features of construction, combination, and arrangement of parts to be hereinafter more fully 35 described, claimed, and illustrated in the accompanying drawing, in which,

Figure 1 is a side elevation of the end of a billiard cue provided with my improved tip; Fig. 2 is an enlarged longitudinal section; and Fig. 3 is a detail perspective view, the tip and ferrule separated, the latter being partly in section.

Referring in detail to the drawing, 5 designates the cue which gradually tapers longitudinally and is slightly reduced in diameter at its smaller end, as indicated at 6. Upon this reduced end of the cue, the metal ferrule 7 is adapted to be engaged. This ferrule, as clearly shown in Figs. 2 and 3 50 of the drawing, is formed from a single piece of metal. The ferrule is produced from a metal tube of requisite length which is entirely open at one end and is provided at its other end with an inwardly extending 55 annular wall or flange 8, the inner edge of said flange defining an opening 9. This an-

nular flange or wall 8 is projected into the body of the tube by means of a suitable die plunger, the body wall of the tube being thus bent inwardly upon itself, as indicated at 10, 60 so that a longitudinal wall of double thickness is provided at this end of the tube projecting outwardly from the flange 8.

The opposite end of the metal tube or ferrule is longitudinally split at spaced points, 65 as at 11, so that the end edge of the tube between these longitudinal splits will have a resilient clamping action and securely clamp or grip upon the reduced end of the tube 6 when the ferrule is forced over the same. 70

The tip 12 for the cue is preferably constructed of leather of high quality, said tip being provided with a rounded or convex head 13 and a slightly reduced cylindrical shank or extension 14. The end face of this 75 reduced shank 14 of the tip is provided with intersecting incisions 15. This shank portion 14 of the tip is of sufficient diameter to fit tightly within the double-walled end of the ferrule 7.

In the use of the device, the split end of the ferrule 7 is first inserted upon the reduced end 6 of the cue, a suitable liquid cement being preferably first placed within the ferrule upon the flange 8 so that the same will be forced through the central opening 9. After applying the liquid cement to the end face of the tip 12, the shank 14 of this tip is then inserted into the outer 85 end of the ferrule and against the flange 8. The liquid cement enters the incisions 15 in the end face of the tip and said cement constitutes a binding agent between the tip 12 and the end of the cue and also between the cue and the tip and the metal flange 8. 90

It will be observed that the incisions 15 in the cue tip are of a length greater than the opening defined by the inner edge of the flange 8 so that the adhesive or cement will pass through said opening and fill the incisions in the manner shown in Fig. 2 of the drawing, whereby the cement will extend around the inner edge of the flange 8 and upon both faces thereof. The cement or adhesive, after hardening, constitutes what is, in effect, a substantially T-shaped connecting element between the end of the cue and the ferrule. Thus, all of the parts are securely united and held together upon the cue. By providing the ferrule having a longitudinal wall of double thickness projecting beyond the end of the cue, the tip 100

105

110

is braced and reinforced, and liability of the same being disconnected from the end of the cue by lateral pressure upon the tip, therefore minimized.

5 From the foregoing description, taken in connection with the accompanying drawing, the construction, manner of use, and several advantages of my invention, will be clearly and fully understood. It will be
10 seen that I have entirely dispensed with the use of screws, pins or other fastening elements so that the tip may be very easily and quickly applied to the end of the cue. After the liquid cement or other adhesive has set or
15 hardened, the tip will be immovably held in place. It is, of course, apparent that the leather tips may be made in various sizes and shapes other than that shown in the drawing and the double-walled end of the
20 metal sleeve or ferrule made of any desired length. The invention, as a whole, may be produced at very small manufacturing cost and provides a reliable and efficient means for easily and quickly repairing billiard
25 cues which is especially advantageous in cases of emergency.

While I have shown and described the preferred construction and arrangement of the several features of my invention, it
30 will be understood that the same is susceptible of considerable modification, and I, therefore, reserve the privilege of resorting to all such legitimate changes as may be fairly embodied within the spirit and scope
35 of the invention as claimed.

Having thus fully described my invention, what I desire to claim and secure by Letters Patent is:—

1. The combination with a billiard cue,
40 of a metal ferrule adapted for engagement upon the end of the cue and having an internal annular flange, an adhesive material disposed between the end face of the cue and said flange, and a tip adapted to be
45 inserted into the outer end of the ferrule and

provided with means to receive the adhesive material when the tip and ferrule are forced inwardly upon the cue, whereby the adhesive, when hardened, forms a connecting element between the flange and the end of 50 the cue.

2. The combination with a cue, of a metal ferrule adapted for engagement upon the end of the cue and having an internal annular flange, an adhesive arranged between 55 the flange and the end face of the cue, and a tip adapted to be inserted into the ferrule having an incision in its end face of a length greater than the diameter of the opening defined by said flange, said incision 60 receiving the adhesive when the ferrule is forced inwardly upon the cue, whereby a substantially T-shaped connecting element is formed between said flange and the end of the cue when the adhesive becomes hard- 65

3. The combination with a cue, of a ferrule consisting of a metal tube having one of its ends turned inwardly and provided with an inwardly projecting annular flange 70 on the extremity thereof, said returned end of the ferrule providing a wall of double thickness, an adhesive arranged between the flange and the end face of the cue, a tip adapted to be inserted into the double wall 75 of the ferrule and having intersecting incisions in its base, said incisions being of a length greater than the diameter of the opening defined by the flange on the ferrule, the adhesive being received in said incisions 80 so that the same extends upon both sides of the flange and forms a connecting element between the flange and the end of the cue when the adhesive is hardened.

In testimony whereof I hereunto affix my 85 signature in the presence of two witnesses.

JOHN R. CLARK.
